UNITED STATES PATENT OFFICE

EVELYN G. LEVKOFF, OF ROCKAWAY PARK, NEW YORK

DESIGN FOR A DISPLAY BOX

Application filed January 12, 1932. Serial No. 42,452. Term of patent 3½ years.

To all whom it may concern:

Be it known that I, EVELYN G. LEVKOFF, a citizen of the United States, residing at Rockaway Park, in the county of Queens and State of New York, have invented a new, original, and ornamental Design for a Display Box, of which the following is a specification, reference being had to the accompanying drawings, forming part thereof.

I claim:

The ornamental design for a display box, as shown.
